UNITED STATES PATENT OFFICE.

CHARLES DAUM, OF FOREST HILLS, NEW YORK, ASSIGNOR TO AMERICAN FIBRE CHAIR SEAT CORP., OF LONG ISLAND CITY, NEW YORK, A CORPORATION OF NEW YORK.

DESIGN FOR A CHAIR SEAT.

Application filed March 1, 1923. Serial No. 5,334. Term of patent 3½ years.

To all whom it may concern:

Be it known that I, CHARLES DAUM, a citizen of the United States, and a resident of Forest Hills, Long Island, in the county of Queens and State of New York, have invented a new, original, and ornamental Design for Chair Seat, of which the following is a specification, reference being had to the

accompanying drawing, forming part thereof.

The figure is a plan view of a chair seat, showing my new design.

I claim:

The ornamental design for a chair seat as shown.

CHARLES DAUM.
